AUTOMOBILE HEATER

Henry J. De N. McCollum, Evanston, Ill.

Application October 10, 1938, Serial No. 234,137

7 Claims. (Cl. 237—12.3)

The invention relates generally to heaters for motor vehicles and more particularly to a control for heaters of the class described that are provided with independent heat generators of the internal combustion type.

In instances where internal combustion heaters are connected to the intake manifold of an internal combustion engine in order to use the vacuum created in the intake manifold as a source of power to carry forward the process of combustion in the heater, the products of combustion are drawn into the intake manifold of the engine where they mix and commingle with the combustible mixtures which are provided by the engine carburetor for engine consumption.

In view of the fact that the products of combustion of such heaters contain inert and non-combustible gases which are of no value for re-combustion purposes in the engine, the combustible mixture going to the engine is correspondingly diluted, and, while the amount of dilution is practically negligible at high engine speeds because of the proportionately large volume of the mixture used at such speeds, yet the degree of dilution becomes critical when the engine is idling and the degrees of vacuum in the engine is very high.

Such a dilution interferes with the correct operation of the engine at idling speeds which can not be eliminated satisfactorily by resetting the idle adjustment of the carburetor.

Consequently, one of the objects of the invention is to provide a control which restricts the flow of burnt gases from the internal combustion heater into the intake manifold of an automobile engine when the engine is idling.

Another object of the invention is to provide a control for an internal combustion heater which reduces the flow of exhaust gases from the heater to the minimum barely necessary to sustain heater combustion when the engine is idling, and returns the flow to a maximum when the engine speed is increased.

Another object of the invention is to provide a device of the class described wherein the flow of diluting burnt gases from the heater to the intake manifold of the engine is proportioned at low engine speeds to the flow of combustible mixtures in the manifold to the engine.

Another object of the invention is to provide a control for internal combustion heaters exhausting into the intake manifold of an engine which may be used as a universal installation with all conventional internal combustion en-

gines to prevent dilution of the intake mixtures by the exhaust of the heater at idling speeds.

Another object of the invention is to provide a device of the class described which is simple in construction and operation, effective in its use and inexpensive to manufacture.

These being among the objects of the invention, other and further objects will become apparent from the drawing herein, the description relating thereto, and the appended claims.

Referring now to the embodiment of the invention shown partly in side elevation and partly in enlarged vertical section in the single view of the accompanying drawing, the internal combustion heater is indicated generally by the numeral 10, and reference may be had to my co-pending application, Serial No. 61,213, filed January 28, 1936, for the structural characteristics thereof, wherein, briefly, air and fuel are drawn into the carburetor 12, through the combustion chamber 14 where the mixture is ignited to form hot gases which are drawn through the radiator unit 16 and discharged through the tube 18 into the intake manifold 20 of an automobile engine (not shown) by the vacuum developed in the manifold 20.

Referring now to that portion of the drawing shown in vertical section, a variable cut-off valve 22 is disposed in the passageway 24 of the tube 18, between the heater 10 and the intake manifold 20. The cut-off valve 22 comprises a fitting 26 having a bore 28 of approximately the same size as the passageway 24 so that the normal flow of exhaust gases through the passageway 24 is unrestricted. A cylindrical plunger 30 provided with a spherical head portion 32 is reciprocally mounted in the fitting for movement in a cylindrical bore 34 that is normal to the bore 28. The plunger 30 is of approximately the same size as the bore 28 whereby movement of the head portion 32 of the plunger into a position intercepting the bore 28 serves as a variable cut-off valve to control the flow of burnt gases through the passageway 24 from the heater 10 to the manifold 20.

Movement of the plunger 30 in its capacity is controlled in the embodiment illustrated by a flexible diaphragm 36 mounted in a suitable casing 38 and carrying an actuator rod 40 which is directly connected to the plunger 30 by a pin 42. The diaphragm 36 divides the casing 38 into sealed compartments 37 and 39. The rod 40 is provided with a reduced end portion 44 providing a shoulder 46 against which the central portion of the diaphragm 36 is held in sealed relation by

a ring 48 swaged on the reduced end portion 44.

The rod 40 extends through the compartment 39 and is held for free reciprocation in response to the movement of the diaphragm 36 by means of a guide flange 50 struck from the casing 38. The compartment 39 is open to atmosphere through an opening 52 and although it will be appreciated that there may be sufficient clearance between the guide flange 50 and the wall of the rod 40 to admit air at atmospheric pressure into the compartment 39, the opening 52 is provided to avoid any danger of improper operation which might otherwise develop if the clearance between the flange 50 and the piston 40 were to become filled or restricted by dirt and other foreign substances.

The casing 38 is mounted relative to the fitting 26 by means of an arm 52, and the compartment 37 which is sealed to atmospheric pressure is connected in open communication with the intake manifold 20 through the tube 54 which leads to the intake manifold through an opening 56 located immediately below or upon the engine side of the throttle valve 58 of a conventional down-draft carburetor (not shown).

A compression coil spring 60 is provided upon the compartment 37 side of the casing to drive the rod 40 downwardly against the force of the vacuum upon the diaphragm so that the plunger 30 is held at a normally open position until such time as the vacuum present in the intake manifold is sufficient to overcome the force of the spring. Moreover, the spring is snugly mounted for operation in the cylindrical portion 59 of a bushing 61 which is threaded to the casing and is connected to tube 54 leading to a port 55 in the extension 65 to the wall of the carburetor. The cylindrical portion 59 is axially aligned with the rod 40 and the coils of the spring 60 cooperate with the reduced portion 44 of the rod to assist the guide flange 50 in maintaining the rod 40 in proper alignment.

Threaded collar 62 and flange 64 are provided for all connections so that in addition to the device being readily assembled or dismantled for repairs, if upon occasion such are required, the device may be installed conveniently as original equipment, or as an accessory for heaters already installed.

In operation the device described is arranged and adjusted to function in the following manner:

The spring 60 used in any particular device is selected to have the necessary tension which, in relation to the area of the diaphragm 36 exposed to the vacuum in the intake manifold, will yield when the vacuum to which the diaphragm 36 is exposed approaches the degree which is present in the intake manifold at idling speeds, when the throttle valve is in dotted line position B. Under these conditions the upper surface of diaphragm 36 is subjected to high vacuum and flexes upwardly to close valve 22 to a sufficient degree to prevent flow of exhaust gases from the heater therethrough in excess of the minimum amount necessary to maintain combustion in the heater. In this way dilution is minimized and lowered to a point which will not materially affect the idling operation of the engine.

As soon, however, as the throttle valve is open slightly, to the dotted line position (A), the pressure in the port 55 rises rapidly to substantially atmospheric pressure. The degree of vacuum at the port 55 is thus critically responsive to the

position of the throttle valve in the nearly closed position of the latter. This fact will be apparent when it is considered that the port 55 is on the intake manifold side of the throttle valve when 5 the valve is completely closed, but that as soon as the valve is slightly opened the port is on the side of the throttle valve opposite the intake manifold, and is thus subjected only partially to the high intake manifold vacuum. As a result of this 10 construction, the diaphragm 36 is quickly responsive to the movement of the throttle valve to and from closed position, and the plunger valve 30 is moved toward closed position only when the throttle valve is substantially completely closed.

Although a single embodiment of the invention has been shown and described herein, it will be apparent to those skilled in the art that various and further uses, modifications and changes may 20 be made without departing from the spirit and substance of the invention, the scope of which is commensurate with the appended claims.

What is claimed is:

1. In a heating system for use with an automotive vehicle having an internal combustion engine with an intake manifold on said engine, an internal combustion heater which exhausts the products of combustion thereof into the intake manifold of the internal combustion engine, 25 a throttle valve between the engine carburetor and the intake manifold of the engine, a casing having an opening in one side thereof, a diaphragm disposed in said casing and dividing said casing into two compartments sealed from each 30 other, resilient means urging said diaphragm in a direction towards the compartment having said opening therein, means connecting the other of said compartments to the intake manifold of an internal combustion engine upon the engine side 35 of said throttle valve closely adjacent the point at which the edge of said valve lies when in closed position, an element connected to said diaphragm and reciprocated thereby an exhaust passageway 40 for said heater, and a removable obstruction in said passageway actuated by said element partially to obstruct said passageway when the degree of vacuum in said intake manifold approaches that developed by the engine at idling speeds, said resilient means operating to hold 45 said obstruction out of said passageway when the degree of vacuum in said intake manifold is other than that developed at approximately idling speeds.

2. In a heater of the class described which 55 exhausts the products of combustion thereof into the intake manifold of an internal combustion engine, the combination of a throttle valve between the engine carburetor and the intake manifold, a casing having an opening therein defining 60 a bore, a diaphragm disposed in said casing normal to the axis of said bore and dividing said casing into two compartments sealed from each other, one of which has said opening therein, resilient means urging said diaphragm in a direction towards the compartment having said opening therein, means connecting the other of said compartments to the intake manifold of an internal combustion engine upon the engine side 65 of the throttle valve thereof when the throttle valve is in closed position and effectively upon the opposite side thereof when said throttle valve is in partly open position, an element extending through said bore connected to said diaphragm and reciprocated thereby, an exhaust passageway 70 for said heater connected to the intake man-

ifold of the engine, and a plunger in said passage-way moved to partly closed position by said element when a high degree of vacuum is created in said intake manifold and opened by said element under the influence of said resilient means when the degree of vacuum is other than a high degree.

3. In a heating system for use with an internal combustion engine, an intake manifold on said engine, an internal combustion heater which exhausts the products of combustion thereof into the intake manifold of an internal combustion engine, the combination of a conduit having a bore of predetermined cross sectional area through which said products of combustion are conducted from the heater to said manifold, a cylinder transverse to and opening into said bore, a piston reciprocally mounted in said cylinder having a headed portion movable to and from a position partially obstructing said bore, and means responsive to the high degree of vacuum in said manifold normally present at approximately idling speeds of said engine for normally holding said piston open at engine speeds other than idling and for moving said piston to a position partly obstructing said bore when said engine is idling.

4. In a heater of the class described which exhausts the products of combustion thereof into the intake manifold of an internal combustion engine, the combination of a conduit having a bore of predetermined cross sectional area through which said products of combustion are conducted by vacuum from the heater to said manifold, a transverse cylinder opening into and of the same size as said bore, a piston reciprocally mounted in said cylinder having a spherical headed portion movable to and from a position partly obstructing said bore, and means responsive to a high degree of vacuum in said manifold for normally holding said piston in partly obstructing position and for moving said piston to non-obstructing position when the degree of vacuum in said manifold is low.

5. For use with an automobile having an internal combustion engine provided with a carburetor and intake manifold, the combination of an internal combustion type heater, a discharge conduit connecting said heater to the intake manifold of said engine to conduct the gases of combustion from said heater to said intake manifold, a regulating valve in said conduit for controlling the flow rate therethrough, a member connecting the carburetor and intake manifold and having a throttle bore therein, a butterfly

type throttle valve in said bore, said member having an opening on the intake manifold side of said throttle valve when the latter is in its closed position, and means connected to said opening and responsive to pressure changes to cause said regulating valve to move toward closed position with increasing vacuum at said opening.

6. For use with an automobile having an internal combustion engine provided with a carburetor and intake manifold, the combination of internal combustion type heater, a discharge conduit connecting said heater to the intake manifold of said engine to conduct the gases of combustion from said heater to said intake manifold, a regulating valve in said conduit for controlling the flow rate therethrough, a member connecting the carburetor and intake manifold and having a throttle bore therein, a butterfly type throttle valve in said bore, said member having an opening on the intake manifold side of said throttle valve when the latter is in its closed position, a casing connected to said opening, a diaphragm in said casing, an operative connection between said regulating valve in said diaphragm and resilient means effective to move said regulating valve to open position whereby pressure decrease at said opening will cause said regulating valve to move toward closed position.

7. In a heating system for use with an automotive vehicle having an internal combustion engine, a carburetor, an intake manifold on said engine, and a throttle valve between the carburetor and the intake manifold of the engine, an internal combustion heater which exhausts the products of combustion thereof into the intake manifold of the internal combustion engine, a conduit connecting said heater to the intake manifold of the engine, a valve in said conduit between said heater and said manifold for controlling the flow of the products of combustion from the heater to the manifold, said valve forming an obstruction capable of only partially cutting off such flow, means holding said valve in a normally open position, and means communicating with the intake manifold side of said throttle valve when the latter is closed and responsive to the high degree of vacuum in said manifold when said throttle valve is closed to move said valve to a position partially cutting off the flow of products of combustion from the heater to the manifold, said means communicating with the carburetor side of said throttle valve when the latter is open, whereupon the valve in said conduit assumes its normal position.

HENRY J. DE N. McCOLLUM.
